UNITED STATES PATENT OFFICE.

FRANKLIN MUZZY, OF BANGOR, MAINE.

IMPROVEMENT IN MACHINES FOR SAWING SHINGLES AND OTHER LUMBER.

Specification forming part of Letters Patent No. 35,832, dated July 8, 1862.

To all whom it may concern:

Be it known that I, FRANKLIN MUZZY, of Bangor, in the county of Penobscot and State of Maine, have invented a new and useful Improvement in Machines for Sawing Shingles and other Lumber; and I do hereby declare the following to be a full and exact description of the same, reference being had to the accompanying drawings, making part of this specification, in which—

Figure I is a top view of my improved machine. Fig. II is a front elevation of the same. Fig. III is a side elevation of the same. Figs. IV and V are fragmentary sections, (on a larger scale,) to be hereinafter referred to. Fig. VI is a vertical section of the carriage at x x . Figs. I and II. Fig. VII is a vertical section of the mechanism represented in Fig. IV, looking in the opposite direction.

Similar marks of reference indicate corresponding parts in the several views.

The nature of my said invention consists, first, in the combination, with a circular saw, of a carriage fed downward by connection with the power which operates the saw in a direction so nearly perpendicular as to present the center of the shingle-block to the upper half of the saw, as will be hereinafter more fully explained; second, in an improved device for changing the motion of the carriage; third, in an improved device for setting the block; fourth, in an automatic device for regulating the feed motion of the carriage to correspond with the width of the block.

To enable others skilled in the art to fully understand and use my invention, I will proceed to describe its construction and operation.

A A A are various parts of the main frame of the machine.

B is a circular saw secured to a shaft, C, which is rotated by a pulley, D. The said shaft is also provided with pulleys E E', of unequal diameter, either of which carries a band, F, which passes around a pulley, G or G', upon a square shaft, H.

I is a pinion journaled loosely on the shaft H, but caused to rotate therewith, when desired, by means of a sliding clutch, J, which is thrown in and out by a horizontal lever, K, fulcrumed at K', and operated by a hand-lever, L. The pinion I meshes with a gear-wheel, M', upon a shaft, M, which, by means of bevel-gears P', communicates motion to a

shaft, P, carrying a pinion, p, near one end. The end of the shaft P, which carries the pinion p, runs in a bearing, p', which is made adjustable in order to throw the said pinion in or out of gear with a rack, r, upon a carriage, 7, in which the shingle-block is secured. The bearing p' of the shaft P is in the upper end of a standard, f, pivoted at f', and having a rigid arm, f'', projecting horizontally from it. A weight, e, is hung at the outer end of the arm f'', the tendency of which is to draw the pinion away from the rack. This tendency is overcome by a heavier weight, g, depending from the outer end of a knee or pressure-cam, a, which is pivoted concentrically with the standard f, and bears against the upper end thereof, so as to press the pinion toward the rack. The pinion is held firmly in gear with the rack while the gate is descending by means of a latch, d, catching under a pin or notch upon the standard, and automatically withdrawn by means of a trip-lever, 5, as hereinafter more fully explained, when the gate has descended as far as needful.

As the carriage 7 approaches the downward termination of its stroke, a pin, b, projecting therefrom, presses against the inclined or curved edge of the pressure-cam a, so as to remove it from the standard f, when the said pressure-cam is caught by a latch, c; and the weight e thereby permitted to draw the pinion p away from the rack r the instant the latch d is tripped.

W is a weight attached to a cord, w, running over pulleys and attached to the carriage so as to elevate it when thus released.

The above devices for throwing the pinion p in and out of gear are more clearly represented by the fragmentary sections, Figs. IV and VII, which show the parts upon a larger scale.

7* 7* are ways securely framed upon the top of the carriage 7.

N is a head-block sliding upon the ways 7* and provided with jaws O O, of any suitable construction, for securing the block or bolt 1 represents the block.

N' N' are ears projecting horizontally from the head-block N.

h h' are racks pivoted to the ears N'.

S is a set-shaft journaled transversely across the carriage and carrying toothed wheels S' Fig. III, which take into the racks h h'.

S^2 is a ratchet-wheel secured to the shaft S near one end.

i is a lever fulcrumed upon the said shaft immediately in front of the ratchet-wheel S^2 and carrying a spring-pawl, t , which takes into the said ratchet-wheel.

m is a stud which the rear end of the lever i strikes in descending, so as to impart rotation to the set-shaft S .

K is a cam which the forward end of the lever subsequently strikes in order to retract the lever and cause the pawl t to engage with another tooth of the ratchet-wheel.

The wheels S' are formed each with one half as many teeth as the ratchet-wheel S^2 , and are so placed upon the shaft that their teeth will act successively upon the racks $h\ h'$, moving the latter alternately to the distance of one tooth each time.

t are spring-catches, (one shown in Fig. III,) taking into the racks $h\ h'$ to hold them stationary when not required to move, but retracted therefrom by either wheel S' which may be in position to move the rack.

The setting devices will be more clearly understood by reference to Fig. V, where they are shown in elevation on a larger scale.

2 is a lever attached to a shaft, 3 , which is journaled in the carriage 7 .

10 is a crank-arm projecting from the opposite side of the shaft 3 .

4 is a rigid rod connecting the crank-arm 10 with the trip-lever 5 , so as to support the latter at any required height. The office of the lever 5 is to retract the latch d , so that the pinion p may be drawn out of gear to permit the carriage to rise after it has descended the required distance. To govern the position of the lever 5 , the lever 2 rests on the top of the shingle-block while the carriage is descending; but as the carriage approaches the extremity of its upward stroke a fixed cam or stud, 6 , depresses the lower end of the lever 5 and thereby elevates the lever 2 clear of the block 1 .

8 are stops or buffers limiting the upward motion of the carriage.

R is a stud projecting downward from the head-block and carrying forward a horizontal slide, R' , to which is attached a hook, R^2 . The office of the said hook is to catch the lever 5 when the head-block reaches its forward position and the shingle-block is exhausted. The lever 5 is thus prevented from tripping the latch d , and consequently the carriage will continue to descend until caught by a hook, R^2 , which holds it until a new block has been supplied.

U is a shaft provided with a hand-lever, U' , and cams U^2 , which, when the lever U' is depressed, withdraw the spring-catches t and hold them out of the racks $h\ h'$, so that the head-block may be moved back for the insertion of a fresh shingle-block.

R^4 is a lever employed to operate the hook R^2 by hand at any other time when it is desired to hold the gage-lever 2 , so that the car-

riage may descend to its lowest position and be there held.

Fig. I represents the head-block retracted ready to receive a shingle-block. Figs. II and III show the carriage at its highest position and the block in position ready for sawing.

The operation is as follows: The carriage is moved down by the pinion p and rack r feeding the block to the saw. The pin b , by pressing against the pressure-cam a , retracts it from the standard f , and it is so held by the latch c . The pinion p is then held in gear only by the latch d . The gage-lever 2 , resting on the shingle-block, holds the trip-lever 5 at such height as that it will strike the latch d as soon as the saw has passed completely through the block. The instant the latch is tripped by the lever 5 , so as to release the standard f , the weight e draws the pinion p away from the rack r , and the carriage being thus released is drawn up by the weight W . When the carriage reaches the upper termination of its stroke, the pin b lifts the latch c , which releases the pressure-cam a , and the pinion is again thrown in gear by the action of the weight g . The carriage then descends again, and the rear end of the set-lever i , striking the stud, rotates the shaft S the distance of one tooth, which, acting upon one of the racks h or h' , moves forward that end of the head-block N , forwarding the shingle-block obliquely, so that the severed piece will be thick at one end and thin at the other. After passing the stud m , the set-lever is retracted by the cam k , so as to be ready for the next stroke, which forwards the other end of the head-block, while that last moved remains stationary. The block is thus worked up evenly, the butt of the shingle being taken from alternate ends. Each rack, when not in motion, is firmly held by the spring-catches t , and each of the latter is retracted, as its rack has to move, by a tooth of the wheel S , the parts being so arranged that the tooth preceding that which acts upon the rack will withdraw the catch, while the wheel which turns without moving the rack does not act upon the catch.

By the combination of levers 2 and 5 the distance to which the carriage descends is made to depend always upon the width of the bolt, so that the carriage moves only so far as is needful to sever the shingle, and loss of time and power is thus avoided. When the head-block moves forward for the last shingle in the block, the slide R advances so far that its hook R^2 catches the gage-lever 2 and prevents it falling, thus causing the carriage to feed down to its lowest point, where it is caught and held by the hook R^2 to permit the attendant to insert a new shingle-block. For this purpose he retracts the catches t by means of the lever U , as before explained, and moves the carriage back to the proper position. The new shingle-block being inserted, the operator unhitches the hook R^2 , when the carriage runs up, and the work proceeds as before. To enable the workman to stop the carriage when down, in

order to turn the bolt, or for any other purpose, the hook R^2 may be operated by hand by means of the lever R , so as to catch the gage-lever 2 in the same way as it is caught automatically when the bolt is worked up.

It will be observed that the perpendicular descent of the carriage causes the saw to strike the center of the bolt and cut as nearly as possible with the grain of the wood. The machine operates with great rapidity, with little power, produces shingles of superior quality, and with the greatest possible economy of lumber.

Instead of the balance-weights upon the latches c and d , small springs may be employed, and springs may also be substituted for the weights e and g , or either of them, these being equivalent devices which do not affect the principle of the invention. The carriage may, if preferred, be elevated by cog-gearing instead of by the weight W .

When the machine is used for sawing box and other boards with parallel sides, the wheels S' are provided with the same number of teeth as the ratchet-wheel S^2 , and so placed upon the shaft that their teeth will act simultaneously upon the racks h h' .

Having thus described my invention, the following is what I claim therein as new and desire to secure by Letters Patent as an improvement in circular saw shingle-machines:

1. Reversing the reciprocating vertical action of the carriage for feeding the bolt to the saw automatically by the operation of the

mechanism or its equivalent connected with the vibrating shaft P , substantially as described.

2. The combination of the latches c d , pressure-cam a , and pivoted standard f , operated by either weights or springs to throw the pinion p in and out of gear, substantially in the manner explained.

3. The combination of the lever i , pawl i' , and wheels S' and S^2 , actuated by suitable studs or cams, m k , so as to move the racks h h' forward alternately or simultaneously, as explained, in connection with a shingle-machine carriage moving in a direction so nearly perpendicular as to present the center of the shingle-block to the upper half of the saw, substantially as set forth.

4. The gage-lever 2 and trip-lever 5, employed, in combination with the latch d , to regulate the motion of a shingle-machine carriage moving so nearly perpendicular as to present the center of the shingle-block to the upper half of the saw, substantially as set forth.

5. The combination of the stud R , slide R' , and hooks R^2 R^3 , operating in the described connection with the head-block N and trip-lever 5 to arrest the motion of the carriage when the bolt is worked up.

FRANKLIN MUZZY.
